 Feigin and Fridman(57) **CLAIM**

The ornamental design for the toy guitar, as shown and described.

DESCRIPTION

FIG. 1 shows a top perspective view of a toy guitar.

FIG. 2 shows a front elevation view thereof.

FIG. 3 shows a rear elevation view thereof.

FIG. 4 shows a left side elevation view thereof.

FIG. 5 shows a right side elevation view thereof.

FIG. 6 shows a top plan view thereof; and,

FIG. 7 shows a bottom plan view thereof.

The broken lines shown in FIGS. 1-3 are included for the purpose of illustrating elements of the toy guitar that form no part of the claimed design.
